CARBURETOR

John R. Emerson, Flint, Mich., assignor, by mesne assignments, to Borg-Warner Corporation, Chicago, Ill., a corporation of Illinois

Application May 23, 1934, Serial No. 727,035

13 Claims. (Cl. 261—75)

The invention relates in general to a carburetor for internal combustion engines and relates in particular to down-draft carburetors of the plain-tube type.

5 An object of the invention is to provide a carburetor of the character described in which the main nozzle feed is brought in smoothly as the engine speed and throttle opening are increased above idling speed and position respectively.

10 More particularly it is an object of the invention to provide a carburetor of the down-draft, plain-tube type in which fuel is conducted from the emulsion tube to the throttle valve in the form of a film during the initial feed of the emulsion tube under low suction.

15 Another object of the invention is to provide in a carburetor a fuel supply nozzle having incorporated therein a bubble diffuser for breaking up vapor bubbles formed in the nozzle.

20 Yet another object is to provide a fuel supply nozzle of novel and improved construction having an air-swept tip causing the nozzle to discharge at unusually low suction.

25 Other objects and advantages will become apparent from the following detailed description taken in connection with the accompanying drawings, in which

30 Figure 1 is a vertical sectional view through one carbureting passage of a duplex carburetor embodying the features of the invention.

35 Figure 2 is a fragmentary view taken along line 2—2 of Fig. 1 and showing in elevation a preferred form of fuel conducting means.

Figure 3 is a view showing a modified form of fuel conducting means.

Figure 4 shows still another form of fuel conducting means.

Figure 5 shows yet another form of fuel conducting means.

40 While the invention is shown in the drawings and will be described hereinafter as embodied in a carburetor of the down-draft type, it is not intended thereby to limit the invention to the specific construction shown but it is intended to cover all modifications and alternative constructions falling within the spirit and scope of the invention as defined by the appended claims.

45 The carburetor shown by way of illustration in the drawings comprises a body member generally 50 designated 5 providing an air intake passage 6, having a downwardly directed venturi 7 therein, and a fuel bowl 8. Secured to the top of the body member 5 is a cover member 9 providing a closure 10 for the top of the fuel bowl and an extension passage 6' for the intake passage 6. A

5 butterfly choke valve 11 controls the air intake passage 6'. Bolted to the bottom of the body member 5 is a throttle body 12 providing a combustible mixture discharge passage 13 which is controlled by a butterfly throttle valve 14 mounted on a throttle shaft 15 extending transversely of the passage. Disposed centrally of the passage 6 and terminating in the venturi 7 is an emulsion tube 16 receiving an emulsion of air and fuel discharged from a main nozzle generally designated 17. The tube 16 is preferably cast as an integral part of the body member 5.

10 In carburetors of the plain-tube type, the suction on the main nozzle is not sufficient to cause a discharge of fuel therefrom when the throttle 15 is substantially closed, as shown in Fig. 1, to reduce the engine to idling speed. Under such conditions fuel is supplied to the engine by means of an idling fuel supply system as is well known in the art. (Such a system is shown in Patent No. 2,050,995 of Aug. 11, 1936, and Patent No. 2,091,436 of Aug. 31, 1937.) The lower or discharge portion of such an idling system is shown in Fig. 1 and comprises an emulsion channel 18 discharging into the passage 13 through an idle fuel jet 19 at a point below the throttle valve 14. The quantity of fuel discharged through the jet 19 is controlled by an adjusting needle 20 carrying a serrated head 21 for convenient adjustment. A secondary idle air vent 22 communicates with the passage 13 above the throttle valve to supply additional air to the emulsion in the channel 18 as well as does an idle control opening 23 communicating with the passage 13 just above the throttle 14 when in idling position. The idle control opening 23 also functions as a fuel discharge means when the throttle valve is opened 25 slightly beyond idle position to aid the idle fuel jet in supplying sufficient fuel.

30 As the throttle is opened to increase the engine speed or to provide additional fuel for climbing or accelerating, the suction on the idling fuel supply system gradually decreases and the suction on the main nozzle 17 increases so that the function of supplying fuel is gradually transferred from the idling system to the main nozzle. Herein the nozzle is located in a bore 24 in the body member 5 and comprises a tubular member 25 shorter than the bore and having a duct 26 extending therethrough. The nozzle terminates in a cap 27 extending into the emulsion tube 16 and having a sleeve portion 27' abutting a shoulder 25' on the member 25. Discharge from the cap takes place through a downwardly directed opening 27". A spring 28 acting in compression between the lower 35

end of the tubular member 25 and a screw cap 29 closing the lower end of the bore 24 retains the nozzle in the upper end of the bore.

- Fuel is supplied to the nozzle from the fuel bowl 8 through a channel 30 communicating with the bore 24 at the space between the lower end of the tubular member 25 and the screw cap 29 and also through a bowl feed jet 31 communicating with an annular groove 32 formed in the member 25. 10 and in turn communicating with the duct 26 therein by means of radial passages 33. An air vent jet 34 draws air from the intake passage 6 and discharges the same into an air vent annulus 35 formed in the member 25 just below the upper 15 end thereof. The air so discharged flows past the end of the tubular member 25 and draws fuel from the duct 26 to form an emulsion of fuel and air subsequently discharged from the nozzle cap 27. 20 In order to prevent vapor bubbles from forming in the duct 26 of the nozzle 17 and carrying with them the fuel in the duct as they rise to the top of the nozzle, means is provided to diffuse the bubbles so formed and break them up into bubbles which are small enough to pass up the bore, 25 to be dissipated at the top of the nozzle, without carrying fuel with them. This means comprises simply a fine wire 36 extending centrally of the duct 26. The wire is fast at its lower end with 30 a flanged collar 36' received in a recess 29' in the screw cap and retained therein by the spring 28 bearing against the flange on the collar.

As above stated, when the throttle is opened to increase the engine speed or to load the engine 35 at any speed, the suction on the manifold side of the throttle is decreased and the fuel feed is accordingly transferred from the idling fuel supply system to the main nozzle 17. Because of the high velocity at which air passes from the nozzle 40 air vent annulus 35 past the end of the tubular member 25, feed from the nozzle starts at very low suction at the nozzle and before the quantity of air passing through the emulsion tube 16 is sufficient to break up the fuel into small drops. 45 The feed from the nozzle 17 at low suction is, therefore, in the form of large intermittent drops. This manner of feed is inherent in plain-tube, 50 emulsion-feed carburetors and is particularly undesirable in carburetors of the down-draft type because the large, intermittent drops fall from the emulsion tube onto the throttle valve 14 where they are broken up and immediately drawn into the manifold thereby supplying a mixture 55 which is intermittently materially richened and thus produces a rolling, irregular operation of the motor. It has long been a problem, therefore, to bring in the feed of the main nozzle smoothly and without the irregular motor operation described.

Means is provided herein for bringing in the 60 feed of the main nozzle smoothly. The means operates by conducting the initial, intermittent discharge from the emulsion tube in the form of a film from the tube to the throttle valve from which it is sucked off at a more uniform rate. 65 The means may take a variety of forms and may be composed of any material capable of conducting fuel from the emulsion tube to the throttle valve in the form of a film as contrasted with drops. A preferred form is shown herein simply 70 as a generally U-shaped member 37 (see Fig. 2) bent from wire. The member is secured to the emulsion tube 16 by means of coils 38 formed by the ends of the wire composing the member and encircling the emulsion tube. The wires extend 75 downwardly along diametrically opposed sides of

the tube 16 and at the discharge end of the tube engage in longitudinal grooves, formed by pairs of lugs 39, to secure the member in position. Immediately below the tube 16 the wires are formed with offsets 40 which bring the wires inwardly beyond the inner circumference of the tube. The member 37 extends downwardly to a point adjacent the throttle valve 14 and in fact preferably contacts the throttle shaft 15 to facilitate the transfer of the fuel from the member to the 10 throttle shaft.

By the use of the member 37 the initial operation of the main nozzle 17 is brought in smoothly and without the customary irregular operation of the engine. At low suction when the discharge 15 from the main nozzle is in the form of large, intermittent drops, substantially all the fuel is conducted down the member 37 in the form of a film and is then sucked from the throttle valve at a 20 comparatively uniform rate. As the throttle opening is increased so that the flow of air through the emulsion tube 16 is at a velocity to cause the drops to be broken up into fine particles, less fuel is conducted down the member 37. However, at such increased throttle opening the feed 25 from the nozzle 17 is no longer intermittent but substantially uniform and the energy of the air flowing within the emulsion tube is sufficient to break the fuel into fine particles so that a mixture of substantially uniform richness is supplied to 30 the manifold.

Modified forms of the conducting member 37 are shown in Figs. 3 to 5. In Fig. 3 the member comprises a plurality of wires 41, the upper ends of which are received in circumferentially spaced grooves 42 formed on the discharge end of the emulsion tube 16. The wires 41 are bent sharply inwardly below the emulsion tube 16 and turned to form a twisted portion 43 which extends downwardly 40 into contact with the throttle shaft 15. With the basket-like construction formed by the inwardly bent wires, the member is effective to catch the drops of fuel which pass centrally through the emulsion tube as well as the fuel that accumulates on the lower edge thereof. The construction, however, is open so as not to interfere with the discharge from the tube when the energy is sufficient to break the fuel into small 45 particles.

In Fig. 4 the conducting member takes the form of a single wire 44 secured at its upper end in the nozzle cap 27 and projecting downwardly through the discharge opening 27' therein and axially of the emulsion tube into contact with the 55 throttle shaft 15. In Fig. 5 the conducting member takes the form of a tapered strip or ribbon 45 disposed diametrically of the emulsion tube 16 and extending downwardly into contact with the throttle valve shaft 15. The ribbon 45 is 60 conveniently attached to the tube by securing the same in slots 46 formed in the tube. In each of the forms the conducting member does not interfere with the discharge from the nozzle under high energy but does conduct the intermittent 65 low energy or low suction discharge in the form of a film from the nozzle to the throttle valve where it is sucked off at a substantially uniform rate and thus prevents the irregular operation resulting from the intermittent drop discharge. 70

I claim as my invention:

1. In a down-draft carburetor for supplying fuel to an internal combustion engine, a body member providing an air intake passage having a venturi therein, a tubular member extending ax- 75

- ially of and discharging into said venturi, a main fuel supply nozzle discharging into said tubular member, a throttle valve controlling the flow of combustible mixture from the carburetor, said main nozzle being inoperative when said throttle valve is substantially closed for idling the engine, an idling fuel supply system having a jet discharging into the carburetor at a point beyond the throttle valve to supply fuel to the engine when the throttle is substantially closed for idling the engine, and means for conducting the discharge from the main nozzle to the throttle valve when the main nozzle is functioning under low suction.
15. 2. In a plain-tube, down-draft carburetor, a body member providing an air intake passage having a venturi, main fuel supply means including an emulsion tube discharging into the venturi and a nozzle discharging into the emulsion tube, a throttle valve controlling the flow of combustible mixture from the carburetor, said main fuel supply being inoperative when said throttle valve is substantially closed for idling the engine, an idling fuel supply system having a jet discharging into the carburetor at a point beyond the throttle valve, and means engaging the main fuel supply means and extending downwardly into engagement with the throttle valve to conduct fuel in the form of a film from said main supply 30 means to said throttle valve when said main supply is operating at low suction.
3. In a down-draft carburetor for an internal combustion engine, a body member providing an air intake passage having a venturi, a float bowl, an emulsion tube disposed longitudinally of and discharging into said venturi, an air bleed main fuel supply nozzle discharging into said emulsion tube fuel drawn by suction from said float bowl, a throttle valve controlling the flow of combustible mixture from the carburetor to the engine, a fuel supply system having a jet discharging into the carburetor at a point beyond the throttle valve to supply fuel for idling speeds of the engine, and means engaging the emulsion tube at its discharge end and extending downwardly to a point adjacent said throttle valve to conduct fuel in the form of a film from said emulsion tube to said throttle valve when said main nozzle is operating at low suction.
40. 4. In a down-draft carburetor, a body member providing an air intake passage having a venturi, an emulsion tube discharging into the venturi, a main fuel nozzle discharging an emulsion of fuel and air into said emulsion tube, a throttle valve controlling the discharge from said nozzle by controlling the flow of air through the intake passage, and means engaging said emulsion tube at its discharge end and extending downwardly into contact with said throttle valve for conducting fuel from said emulsion tube to said throttle valve in the form of a film to bring in smoothly the operation of said main nozzle.
45. 5. In a plain-tube, down-draft carburetor for an internal combustion engine, a body member providing an air intake passage having a venturi, an emulsion tube discharging into the venturi, a main fuel nozzle discharging into said emulsion tube, a throttle valve for controlling the supply of combustible mixture from the carburetor to the engine, and means for bringing in smoothly the operation of said main supply nozzle comprising a U-shaped wire member secured to said emulsion tube in contact with the discharge end thereof and extending downwardly into contact with said throttle valve.
6. In a plain-tube, down-draft-carburetor, a body member providing an air intake passage having a venturi, an emulsion tube discharging into the venturi, said emulsion tube having at its lower end pairs of lugs forming longitudinal 5 grooves disposed diametrically opposite each other, a main fuel supply nozzle discharging into said emulsion tube, a throttle valve for controlling the supply of combustible mixture from the carburetor, a throttle shaft supporting said throttle valve and means for bringing in smoothly the operation of said main supply nozzle comprising a U-shaped wire member bent at its free ends to form coils encircling said emulsion tube and extending downwardly into contact with said 10 throttle shaft, said member engaging in the grooves formed in the emulsion tube and being offset inwardly immediately below the tube.
7. In a plain-tube, down-draft carburetor, a body member providing an air intake passage 20 having a venturi, an emulsion tube discharging into the venturi, a main fuel supply nozzle discharging into said emulsion tube, a throttle valve for controlling the flow of combustible mixture from the carburetor, and a single wire projecting 25 from the nozzle through the discharge opening therein and extending downwardly centrally of the emulsion tube into contact with said throttle valve.
8. In a plain-tube, down-draft carburetor, a body member providing an air intake passage having a venturi, an emulsion tube discharging into the venturi, a main fuel supply discharging into said emulsion tube, a throttle valve for controlling the flow of combustible mixture from the carburetor, and a flat ribbon disposed diametrically of said emulsion tube and extending downwardly into contact with said throttle valve to conduct fuel in the form of a film from the emulsion tube during operation of the main nozzle 40 at low energy.
9. In a carburetor a main body member providing a carbureting passage and a fuel bowl, an emulsion tube integral with said body member disposed longitudinally of the passage and opening to the passage at both ends, an inwardly and upwardly extending bore in said body member communicating at its lower end with the fuel bowl and terminating at the other end in said emulsion tube, a nozzle cap in the bore projecting 50 outwardly thereof into the emulsion tube and discharging in the direction of air flow through the tube, a tubular member in the bore spaced from the cap to provide therewith a discontinuous duct leading from the fuel bowl to the emulsion tube, 55 said member being formed with an air vent annulus at the end adjacent the cap, and an air vent jet discharging into the annulus.
10. In a down-draft carburetor a main body member providing a carbureting passage and fuel bowl, a downwardly discharging emulsion tube disposed longitudinally of the passage, a bore leading from the fuel bowl to the upper end of said emulsion tube, means forming a shielded opening from said bore into the emulsion tube 60 discharging in the direction of flow therethrough, a tubular member fitting snugly within the bore and terminating in a reduced end spaced from the end of the bore, said member having a duct therethrough, and an air vent jet opening upwardly in the passage and discharging into the bore opposite the reduced end of the tubular member whereby the air sweeping past the end of the member draws fuel from the duct.
11. In a down-draft carburetor a main body 75

- member providing a carbureting passage and a fuel bowl, an emulsion tube disposed longitudinally of the passage, a bore leading upwardly from the fuel bowl to the emulsion tube, a nozzle cap with a passage therethrough fitting snugly in the upper end of the bore and projecting outwardly thereof into said emulsion tube, a tubular member having a duct extending longitudinally therethrough fitting snugly within the lower portion of the bore and terminating short of the passage in the cap to provide a discontinuous duct leading from the fuel bowl to the emulsion tube, an air vent annulus formed about the end of the member adjacent the cap, an air vent jet opening upwardly into the passage and discharging into the annulus to draw fuel from the duct as the air sweeps past the end of the member, and a fine wire extending through the duct in the member to diffuse vapor bubbles formed therein.
12. In a down-draft carburetor for supplying fuel to an internal combustion engine, a body member providing an air intake passage having a venturi therein, a tubular member extending axially of and discharging into said venturi, a main fuel supply nozzle discharging an emulsion of fuel and air into said tubular member, a throt-

tle valve controlling the flow of combustible mixture from the carburetor, said main nozzle being inoperative when said throttle valve is substantially closed for idling the engine, an idling fuel supply system having a jet discharging into the carburetor at a point beyond the throttle valve to supply fuel to the engine when the throttle is substantially closed for idling the engine, and means depending from the discharge end of said tubular member for arresting drop discharge therefrom when the main nozzle is functioning under low suction and bringing in smoothly the operation of the main nozzle.

13. In a down-draft carburetor, a body member providing an air intake passage, a tubular member extending longitudinally of the passage and discharging thereinto, a main fuel nozzle discharging into said tubular member, a throttle valve located posterior to said nozzle controlling the discharge therefrom by controlling the flow of air through the intake passage, and means engaging said tubular member at its discharge end and extending downwardly into contact with said throttle valve for conducting the low suction discharge of said nozzle in the form of a film to the high suction edge of said throttle valve.

JOHN R. EMERSON.
